SAFETY DEVICE FOR GAS-LINE LEAKAGE

Guy Maynard, Lexington, Mass.

Application February 26, 1938, Serial No. 192,856

9 Claims. (Cl. 48—193)

Gas lines leading into buildings frequently break or crack, due to settling ground, freezing and thawing, etc., and the leaking gas tends to follow the pipe-line into the building for the reason that a space forms along the pipe-line as a result of expansion and contraction of the pipe-line, thereby subjecting the buildings and their occupants to the hazards of explosions, asphyxiation, etc.

Objects of the present invention are to provide a device for preventing the leaking gas from flowing into the building and for venting it to the atmosphere outside the building, and to provide the device in a form which is simple and economical to construct, which may be installed quickly and easily on a pipe-line already installed and which is durable and effective in use.

In one aspect the invention involves a seal casing and a vent casing which may be separately applied to a pipe-line and then attached together, after which the seal casing may be filled with sealing material.

In other aspects the invention involves a slotted casing which may be fitted over a pipe-line after the pipe-line is installed, flaring slots or other means to accommodate pipes of different sizes, detachable means for suspending the seal casing on the pipe-line while the casing is being filled with sealing material, and other features hereinafter disclosed and claimed.

For the purpose of illustration typical embodiments of the invention are shown in the accompanying drawing in which

Fig. 1 is a vertical sectional view of an installation;

Fig. 2 is an end view, viewed from the house side, with parts in section;

Fig. 3 is an end view of the vent casing viewed from the end away from the house;

Fig. 4 is a section on line 4—4 of Fig. 2;

Fig. 5 is an end view of a modified seal casing viewed from the end away from the house;

Fig. 6 is a section on line 6—6 of Fig. 5;

Fig. 7 is a perspective view of inserts for use in the embodiment shown in Figs. 5 and 6;

Fig. 8 is an end view showing the method of applying the seal casing to the pipe-line; and

Fig. 9 is an end view of the seal casing applied to the pipe-line, viewed from the end away from the house.

The particular embodiment of the invention chosen for the purpose of illustration comprises a vent casing V and a seal casing S for application to a pipe-line I just outside of the foundation 2 of a building. The outer and inner

walls 3 and 4 of the vent casing are provided with slots 5 and 6 flaring to the bottom of the casing which is open. The slot 5 is somewhat deeper than the slot 6 and at its closed end is provided with a lug 7 seating on top of the pipe-line to provide clearance spaces 8 through which leakage gas following the top of the pipe-line can pass into the vent casing 3. The upper end of the vent casing is provided with a threaded boss 9 to receive a vent pipe 10 extending a suitable distance above the ground and carrying on its upper end a hood 11 and a screen 12. The vent casing is also provided with slots 13 to receive bolts 14 for attaching the vent casing to the seal casing after the two casings have been separately applied to the pipe-line.

The seal casing shown in Figs. 1, 2, 4, 8 and 9 is open on the end next to the foundation of the building and the other end is provided with a slot 15 extending downwardly from the open top of the casing. This end wall is also provided with opening 16 to receive the bolts 14. Extending through aligned openings in the side walls of the seal casing are bolts 17 for supporting the casing on the pipe-line. To apply this seal casing to a pipe-line after the pipe-line has been installed the casing is fitted over the pipe-line upside down as shown in full lines in Fig. 8 and then rotated 180° as indicated by the arrow and broken lines to the position shown in Fig. 9. The bolts 17 are preferably applied while the casing is still in inverted position so that the casing is supported on the pipe-line by the bolts during and after rotation.

In making the installation the procedure is preferably as follows: The seal casing is first applied to the pipe-line as above described, the vent casing is then fitted downwardly over the pipe-line to the position shown in Fig. 1, and the bolts 14 are then applied to secure the two casings together. With the open end of the seal casing held tightly against the foundation 2 the casing is filled with pitch, asphalt or other suitable sealing material as indicated at 18 in Fig. 1, all cracks at each end of the seal casing being filled with packing material before the sealing compound is poured. At any convenient time after the sealing compound has set, earth may be filled around and over the casings to the desired level.

From the foregoing it will be evident that the flaring slots 5 and 6 in the vent casing will accommodate pipes of different diameters and that the slot in the seal casing may flare upwardly for the same purpose, the slots 13 permitting the

two casings to be secured together at different relative elevations. Instead of using flaring slots the slots may be made large enough to accommodate the largest size pipe used for gas lines, as indicated at 19 in Figs. 5 and 6, with a flange 5 20 forming a U-shaped recess 21 to receive inserts of different sizes such as shown at 22 and 23 in Fig. 7.

According to the present invention leakage gas 10 tending to follow the upper side of the pipe-line into the building is effectively blocked by the seal casing and its contents and is permitted to escape to the atmosphere through the vent casing and the vent pipe 10.

15 It should be understood that the present disclosure is for the purpose of illustration only and that this invention includes all modifications and equivalents which fall within the scope of the appended claims.

20 I claim:

1. A safety device for preventing leaking gas from following a pipe-line into a building comprising a hollow vent casing and a hollow seal casing each having aligned openings to permit the casings to be fitted over a pipe, the vent casing having an opening in its upper portion to permit the escape of gas, and means for interlocking the two casings against angular movement relative to each other about the pipe-line.

25 2. A safety device for preventing leaking gas from following a pipe-line into a building comprising hollow separate interconnected seal and vent casings having slots to permit the casings to be fitted over a pipe-line which has been installed, the vent casing having an opening in its upper portion to permit the escape of gas, and means for interlocking the two casings against angular movement relative to each other about 30 the pipe-line.

35 3. A safety device for preventing leaking gas from following a pipe-line into a building comprising hollow separate interconnected seal and vent casings having slots extending to the top and bottom of the casings respectively to permit the casings to be fitted over a pipe-line which has been installed, the vent casing having an opening in its upper portion to permit the escape of gas.

40 4. A safety device for preventing leaking gas from following a pipe-line into a building comprising hollow separate interconnected seal and vent casings open at the top and bottom respectively and having slots extending to their open sides to permit the casings to be fitted over a pipe-line which has been installed, the vent casing

having an opening in its upper portion to permit the escape of gas.

5 5. A safety device for preventing leaking gas from following a pipe-line into a building comprising hollow separate interconnected seal and 10 vent casings open at the top and bottom respectively and having slots extending to their open sides to permit the casings to be fitted over a pipe-line which has been installed, the vent casing having an opening in its upper portion to permit the escape of gas and certain of said slots flaring toward their open ends to fit pipes of different sizes.

15 6. A safety device for preventing leaking gas from following a pipe-line into a building comprising a seal casing having an opening in a side wall to permit the pipe-line to pass therethrough and an opening in the top through which the casing may be filled with sealing material after it is applied to the pipe-line, and means on the 20 side of said casing remote from the building to permit the escape of gas upwardly from the pipe-line.

25 7. A safety device for preventing leaking gas from following a pipe-line into a building comprising a seal casing having a bottom and side walls, one side wall having a slot extending from the top part way toward the bottom to receive the pipe-line, the opposite side of the casing having an opening to be closed by the foundation 30 of the building so that the casing may be filled with molten sealing material, and means on said first side of the casing to vent gas upwardly from the pipe-line.

35 8. A safety device for preventing leaking gas from following a pipe-line into a building comprising a seal casing having a slot extending downwardly thereinto from the top to receive a pipe-line, and detachable means for suspending the casing on the pipe-line while it is being 40 poured with sealing material.

45 9. A safety device for preventing leaking gas from following a pipe-line into a building comprising a hollow vent casing and a hollow seal casing each having aligned openings to permit 50 the casings to be fitted over a pipe, the vent casing having an opening in its upper portion to permit the escape of gas, one of said casings having a vertical slot, and means extending through said slot for interlocking the two casings against angular movement relative to each other about the pipe-line.

GUY MAYNARD.
